Primary Examiner — Samantha Wood*Assistant Examiner* — Aula Soroush(74) *Attorney, Agent, or Firm* — Bayramoglu Law Offices LLC(57) **CLAIM**

The ornamental design for a cat tree, as shown and described.

DESCRIPTION

FIG. 1 is a perspective view of a cat tree showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines illustrate portions of the cat tree and form no part of the claimed design.
